UNITED STATES PATENT OFFICE.

ALBERT E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR APPLYING COATINGS.

1,410,574.

Specification of Letters Patent. Patented Mar. 28, 1922.

Application filed December 26, 1918. Serial No. 268,356.

To all whom it may concern:

Be it known that I, ALBERT E. JOHNSON, a citizen of the United States, residing at Beverly, in the county of Essex and State of Massachusetts, have invented certain Improvements in Machines for Applying Coatings, of which the following description, in connection with the accompanying drawings, is a specification, like reference characters on 10 the drawings indicating like parts in the several figures.

This invention relates to machines for applying coatings such as liquid coloring materials to boots and shoes. A particular object of the invention is to provide a machine suitable for use in applying coatings to the edge surfaces of soles and heels after they have been incorporated in shoes in the process of shoe manufacture, but it will be apparent from a consideration of the construction hereinafter described that the invention is not thus restricted in its application and that a machine embodying novel features of the invention is susceptible of a variety of 25 uses.

In finishing operations on some types of shoes, a very quickly drying enamel or paint is used to cover and beautify the edges of the sole and heel of a shoe. This enamel or paint is usually applied by the aid of a brush which is first dipped into the paint and then carried to the edges of the sole and heel, the operative holding the shoe in one hand and the brush in the other. It will be apparent that as thus carried out the operation is slow and the results are far from uniform, since, for example, the width of the edge surface varies and a larger quantity of the paint is likely to be applied to some portions of the surface than to others. Furthermore, the paint dries so quickly that any overlapping of the strokes of the brush is apt to mar the appearance of the finished surface.

It is an important object of the present invention to provide a machine organized to apply various kinds of coatings, such as blackings, paints, and quick drying enamels, to the edges of the soles and heels of completed shoes, so as to improve the quality of the work and also to increase the quantity of work that an operative may perform in a given time. Important features of the invention reside in novel means for effecting 50 the application to the work of coloring material in the form of spray together with im-

proved means for determining the position of the work relative to the spraying nozzle.

A feature of marked importance consists in the construction and arrangement by 60 which the amount of spray delivered to the work is controlled by the work itself so that as variations in certain characteristics of the work occur the spray is automatically regulated in accordance therewith.

In another aspect, the invention comprises an organization in which work engaging or measuring means associated with the spray nozzle is operative to control the nozzle in accordance with characteristics such as 70 dimensions of the work presented for the spraying operation.

Other features of the construction are designed particularly to admit of rapid and effective removal of the spray material from 75 the nozzle and its supplying conduit whenever work is to be discontinued for a considerable period of time as, for instance, at the end of the working day. This is of no little importance since some of the enamels 80 dry so quickly that if not removed effectively at the proper time they are likely to occlude the passageways of conduit and nozzle.

Other objects and features of the invention will be apparent from the following detailed description and will be pointed out in 85 the claims.

In the drawings:

Fig. 1 is a side elevation of a spraying machine representing one embodiment of my 90 invention;

Fig. 2 is a section through the nozzle mechanism of the machine along the line 2—2 of Fig. 1;

Fig. 2^a is a similar view to that of Fig. 2 95 showing the parts slightly enlarged and in a different position relative to each other from that which they occupy in Fig. 2;

Fig. 3 is a front view of the machine shown in Fig. 1;

Fig. 4 is a view of the front portion of the machine illustrating a slight modification;

Fig. 5 is a detail view showing a slide for moving a part of the conduit;

Fig. 6 is a detail view along the line 6—6 105 of Fig. 1, and

Fig. 7 is a detail view in perspective of the work positioning means shown in side view in Fig. 4.

In the illustrative machine, there is provided a tank or receptacle 8 for the blacking or other spray material, a bracket 10

extending from the frame 12 being provided as a suitable support for the receptacle. Mounted in brackets 10 and 14 is a vertical shaft 16 which is suitably journaled in the bottom of the receiver to project therethrough and operate a stirrer 18 having the function of keeping the liquid contents of the receptacle of uniform consistency. Vertical shaft 16 may be driven by any suitable means, that shown in the present construction comprising bevel gears 20 and 22 operatively connecting the shaft 16 with a horizontal shaft 24 carrying a pulley 26 arranged to be driven from any suitable source of power. Connecting the receptacle 8 with the nozzle 28 is a pipe or conduit comprising preferably a relatively movable portion 30 and a stationary portion 32, the latter being supported at each end by a washer-like structure 33 having a cross-bar 35 (Fig. 6) and opening at 34 into the fluid chamber 36 of the nozzle. As shown, the movable part 30 of the pipe or conduit for the liquid extends well down into the receptacle 8 to a point just above the stirrer. Surrounding the conduit throughout the middle portion thereof is a hollow structure 38 having a passageway 40 for compressed air which is admitted through the pipe 42, the latter being connected to a reservoir 44 for compressed air which may be supplied according to any of the well-known methods. The supply of air for the spraying operations is controlled by a valve 46 of any ordinary construction located in the portion 48 of the pipe 42, the said valve being controlled by means under the control of the operator comprising, in the construction shown, a link 50 attached to the valve at one end and at its other end to a second link 52 having its lower end attached at 54 to a lever 56 pivoted at 58 to the frame of the machine and arranged to be operated from a treadle (not shown) by means of a connecting rod 60. Removably attached to the hollow structure 38 at the front part thereof is the nozzle structure 28 which is constructed as shown most clearly in Fig. 2 to provide passageways for the fluid and other passageways for the air which serves to force the fluid from the nozzle under pressure. The upper portion of the nozzle structure is preferably in the form of a hollow casting 62 having side walls 64 to which are attached by screws or other suitable fastening means the thin side plate 66 arranged to converge downwardly to the outlet of the nozzle, the side plate 66 being continuous around the end portions of the nozzle and being held in place by end plates 68 and 70. Since the side plates 66 are relatively thin and flexible a member 72 is provided for engaging the lower edges of the same throughout their lengths, the said member being secured detachably by a fastening at 74 at one end thereof and by screw threaded fastenings 76 at its other end. This member 72 constitutes the real outlet of the nozzle, the size of which is controlled by a slide 78 in a manner to be hereinafter described. Inside of the casting 62 there is positioned a smaller similarly shaped member 80 constituting in effect a flaring continuation of the conduit 32, the two being joined as heretofore pointed out to communicate with each other at the point 34. The sides and ends of the member 80 have secured thereto throughout the continuous lower edge thereof a relatively thin flexible extension 82 with downwardly converging sides extending at the lower ends thereof almost into the plane of the lower edges of the sides 66. Inside of the member 80 is a long wedge shaped member 84 shown in cross section in Fig. 2 and having the function of controlling the amount of fluid which can pass from the fluid chamber 36. In order to adjust the member 84, there is provided a link 86 securely attached thereto by a pin 88 and having at its upper end a screw threaded portion designed to be engaged by a correspondingly threaded nut 90 which is screw threaded into an opening in the upper part of the casting 62. Upon turning the nut 90, the link 86 and with it the wedge 84 are adjusted in a vertical direction toward and from the outlet of the nozzle, and because of the difference in pitch of the interiorly and exteriorly threaded portions of the nut 90 the member 84 may be adjusted with the required fineness and precision to control accurately the amount of liquid at the outlet of the nozzle. Whereas in Fig. 2 the parts are so adjusted as to shut off the air and the fluid at the outlet of the nozzle, the showing of Fig. 2a is such that these same parts are shown so disposed as to permit air to pass along the passageways 92 and fluid along the passageways 94 from the fluid chamber 36. In this connection it should be pointed out that the air passageway 40, which surrounds the stationary part 32 of the conduit for the spray material and also the upper portion of the movable part 30 of the conduit, communicates at one end with the receptacle 8 and at its other end, indicated at 93, with the air chamber 95 in the nozzle.

In order to position the work properly at the outlet of the spray nozzle there is provided a member 96 in the form of a rotatably mounted disk carried by an arm 98 detachably secured to one end of the nozzle structure 28. This disk is designed to enter the rand crease of the shoe as indicated by dotted lines in Figs. 1 and 4 to operate as a gage for the work and to serve also as a shield to prevent application of the liquid to portions of the shoe above the heel or sole edges. Preferably, a work rest 100 is also provided against which the tread surface of the heel is placed and which co-oper-

ates with the disk member 96 in positioning the work. This work rest comprises, in addition to the plate 102, which engages the tread surface of the heel, a plate 104 hinged 5 for limited movement to one edge of the plate 102 and pressed upon by a spring actuated member 106 to cause the plate 104 to engage the breast surfaces of heels formed at various angles with respect to the tread 10 surfaces thereof. Attached to plate 102 is a block 108 having secured thereto cleats 110 provided with beveled edges 112 arranged to engage correspondingly beveled edges on a support 114, the arrangement providing 15 for sliding movement of the work rest 100 on the supporting member 114, a pin 116 being arranged to engage another pin 118 to limit the movement of the work rest on said supporting member. Preferably, the supporting 20 member 114 is pivotally mounted for limited movement in a slot in the end of the shaft 120, said shaft being rotatably and slidably mounted in a bearing 122 on the frame of a machine. In order to hold the 25 shaft 120 projected toward the right in Fig. 1 in a position to present the work rest in a location adjacent to the disk member 96 there is provided a spring 124 mounted at one end in the boss 126 on the frame of the 30 machine and arranged to engage with its other end the end surface 128 of the shaft 120, a collar 130 being adjustably secured to the shaft to determine the extent of projection of the shaft toward the right in Fig. 35 1. Mounted upon a stud 132 is an arm 134 having a segmental rack 136 at its upper end arranged in constant mesh with a gear 138 secured to shaft 120 by means of the ordinary key and slot connection to permit of 40 the sliding movement of said shaft as above described. Selectively engaged in any one of a plurality of openings 140 in the arm 134 is one end of a coiled spring 142 so arranged as to tend constantly to return said 45 arm to a position of rest in which a stop 144 carried thereby engages with a portion of the machine frame 12. The operation of this part of the mechanism may be briefly stated as follows:

50 A shoe positioned for the spraying operations is so arranged that the disk member 96 engages in the rand crease above the heel while at the same time the tread surface of the heel engages the plate 102 of the work rest 100, the work rest being so arranged in connection with its supporting shaft 120 that the lowest heel will be pressed more or less firmly against the member 96 by the action of the spring 124. At the beginning of the 55 spraying operation, a heel engaged with its breast portion against the plate 104 is positioned with one breast edge thereof substantially in line with the outlet of the nozzle. The heel will then be turned at a regular 60 rate so as to present the entire curved sur-

face thereof to the spray, the work rest turning with the heel and the member 96 constantly engaged in the rand crease. During the turning operation there will also be some shifting of the work rest 100 transversely 70 of a supporting member 114. Coincidently with the rotation of the work rest 100 and its supporting shaft 120, the arm 134 is swung about the stud 132 against the action of the spring 142 which operates upon removal of the work to return the shaft 120 and the work rest carried thereby back to initial position in so far as rotation of the shaft can effect that result, it being understood that the work rest and especially the 80 plate 100 is not necessarily brought back to initial position determined by the proper amount of relative sliding movement of the plate 100 and its supporting member 114, relative movement of these parts being 85 variable within limits determinable as heretofore pointed out by engagement of the pins 116 and 118.

In connection with the work rest, its supporting shaft 120 and the spring 124 which 90 constantly urges the shaft and work rest to the limit of their movement in one direction and toward the relatively stationary member 96, it is pointed out that these parts constitute in effect a work measuring mechanism 95 automatically adjustable to various sizes of heels and to the varying height of each individual heel during rotation thereof beneath the spraying nozzle. In connection with the work rest and with the described 100 work measuring mechanism there is provided a means for controlling and regulating the spray with respect to the requirements of the work. In the present embodiment of the invention, the controlling means for the 105 nozzle comprises a member or slide 78 operated to effect constantly the most precise adjustments thereof by means associated with the measuring means for the work and consisting preferably of a cam member 146 110 mounted fixedly on the shaft 120 and arranged to engage rotatably in a slot 148 in a block 150 attached to an intermediate portion of the member 78. The arrangement is such that movements of the work rest 100 115 toward and from the guiding member or abutment 96 is accompanied by corresponding movements of the member 78, slideable in a bracket 151 and in nozzle 28, not only during the insertion of heels of different 120 dimensions but also during movements of the work rest relatively to the member 96 while each individual heel is being turned to provide for the spraying of the curved surface thereof. The member 78 thus regulates the width of the spray in exact accordance with the height of the curved surface of the heel as the said heel varies in height in 125 passing from one breast edge of the heel around to the other breast edge. It will be 130

apparent, then, from the described construction that the operator has only to place the shoe in proper position against the work positioning members 96 and 100 to turn the 5 same during the spraying operation, since the spray is automatically regulated to the requirements of the work by the means described.

At the end of the day's work it is important 10 that the spray nozzle and the conduit leading thereto should be cleared of the spray material which otherwise might harden in the passageways and finally cause occlusion of the same. In order to effect this 15 operation the conduit has been made in relatively movable sections and the nozzle parts have also been constructed and arranged for movement relatively to each other to assist in the removal of the spray material from 20 the nozzle by means of the compressed air supply. According to the preferred construction, the movable portion 30 of the conduit is carried by a slide 156 mounted and normally held tightly between projecting 25 portions 158 of the hollow tubular structure 38. As shown most clearly in Figs. 1 and 5, the slide extends across the passageway 40 for the compressed air and normally holds the movable conduit 30 centrally with respect 30 to said air passage and in communication with the stationary part 32 of the conduit. By loosening the tightening screws extending between the projections 158 the slide 156 may readily be displaced to the left 35 in Fig. 5, thus moving the movable portion 30 of the conduit out of alignment with the stationary portion 32 and bringing an opening 160 in the cross bar 162 of the slide opposite the end of the stationary portion 32 40 of the conduit so that air under pressure may enter the conduit and passing therewith remove the fluid therefrom and also from the fluid chamber 36 and the passageways 94 of the nozzle, thus effecting a complete 45 removal of the fluid from these parts. In order to make the air pressure greater and more effective, the construction of the nozzle is such as to permit the cutting off of the air outlet of the nozzle, this being accomplished 50 by lowering the member 80, 82 so that the lower converging edges of the latter will completely close the air passages 92 as disclosed in Fig. 2 of the drawings, lowering of the member 80, 82 being effected 55 by the proper manipulation of the set screws 164, 166. Thus with the air outlet closed in the nozzle the air under pressure must find its way through the stationary conduit 32 and the expanded flaring end thereof 60 which constitutes the chamber 36 in the nozzle and finally along the passageways 94, thus effecting the removal of the fluid under greater air pressure. After the cleaning operation, the member 80, 82 may be raised 65 to its normal position by means of set screws

166 and firmly secured therein by the co-operation of the two set screw members 164, 166 after which the slide 156 will be returned to its normal position, re-alining the movable and stationary portions of the conduit, thus placing the machine in condition for use in spraying operations. Obviously, adjustment of the member 80, 82 may be utilized to vary the size of the air passages 92 in the nozzle in accordance with the requirements of the work. 75

In a modification of the invention shown in Fig. 4, the spray nozzle 28^a is much lessened in width in comparison with the nozzle disclosed in Fig. 1, since the nozzle of the modification is intended to operate upon the edge of the sole, and is adapted for ready substitution for nozzle 28 on the head of the machine. An accompanying change consists in the substitution of another form 85 of work rest designed to engage the bottom of the sole and shown as comprising a roll 170 mounted rotatably on a support 172 pivotally mounted at 173 in the shaft 120 and designed to be quickly substituted for 90 the work rest 100 and its support 114 made use of in operating on the heels of shoes. In addition to the roll 170 there is mounted on the member 172 a combined shield and edge guide 174. Otherwise the construction 95 and mode of operation of the device is the same as that of the machine already described, regulation of the spray being effected through the control of the sliding member 78 by means of the work contacting roll 170 100 as will be obvious from the foregoing description and from an inspection of Fig. 4.

In operating the machine, the operator places a shoe with the rand crease thereof engaged with the member 96 and with either 105 the work rest 100 or the roller 170 engaging the tread surface of the heel or of the sole, as the case may be, and then depresses the treadle to open the air valve 46 to permit of the inflow of air under pressure, thus forcing the spray material from the nozzle on to the work while the same is being turned to bring the various portions thereof in line with the spray, and finally releases the treadle and removes the shoe at the end of 110 the spraying operation, automatic control of the spray in accordance with the requirements of the work making it necessary only that the operator maintain the shoe in contact with the work positioning means and 115 turn and otherwise move the shoe at the rate required to obtain the best results. 120

Having described my invention, what I claim as new and desire to secure by Letters Patent of the United States is:

1. In a machine of the class described, a spray nozzle, and means for ejecting spray from said nozzle constructed and arranged to be controlled by varying characteristics of the work in its presentation to the machine. 130

2. In a machine of the class described, a spray nozzle, and means controlled in accordance with varying dimensions of the work for determining the amount of spray ejected from said nozzle. 5
3. In a machine of the class described, a spray nozzle, a work rest for positioning the work with respect to the nozzle, and means controlled by movement of the work rest for determining the width of the spray from the nozzle. 10
4. In a machine of the class described, a spray nozzle, and means for regulating automatically the dimensions of the jet of spray ejected from said nozzle. 15
5. In a machine of the class described, a spray nozzle, a work rest for positioning the work with respect to the nozzle, and means controlled automatically from the work rest for regulating the spray from the nozzle. 20
6. In a machine of the class described, a spray nozzle, a member for engaging in the rand crease of a shoe, a member for engaging another portion of the shoe, and means for regulating the spray from said nozzle constructed and arranged to be controlled by relative movement of said members. 25
7. In a machine of the class described, a spray nozzle, a member for engaging in the rand crease of a shoe, a movable member for engaging another portion of the shoe to measure variations in certain structural characteristics of the shoe, and means controlled by said measuring means to regulate the spray from the nozzle. 30
8. In a spraying machine, a spray nozzle, means for measuring the work to which the sprayed material is to be applied, and means controlled by said measuring means for regulating the spray from the nozzle. 40
9. In a spraying machine, a spray nozzle, means for automatically measuring the work to which the sprayed material is to be applied, and means controlled by said measuring means for adjusting the size of the outlet of the nozzle. 45
10. In a spraying machine, a spray nozzle, a member adapted to engage in the rand crease of a shoe to position the shoe and limit the application of spray thereto, and a member for engaging another portion of the shoe for controlling automatically the width of the spray from said nozzle. 50
11. In a spraying machine, a spray nozzle, a work rest mounted for rotation so as to present all portions of the work to the nozzle, and means for returning the rest to initial position. 55
12. In a spraying machine, a spray nozzle, an abutment for engaging a shoe to position the same properly with respect to the nozzle, and a work rest mounted for movement in a plurality of directions and along different paths so that all portions of the work may be presented to the nozzle. 60
13. In a spraying machine, a spray nozzle, a work rest mounted for rotation so as to present all portions of the work to the nozzle, means for returning the rest to initial position, and means for automatically adjusting the work rest to variations in the work during rotation thereof. 70
14. In a machine of the class described, a spray nozzle, a work rest against which a shoe is pressed, the position of which is controlled by the shoe during presentation thereof to the nozzle, and means associated with the work rest for controlling the spray from the nozzle. 75
15. In a spraying machine, a spray nozzle, means for measuring the work upon presenting the same in proper position to receive spray from the nozzle and constructed and arranged to move with the work as the latter is turned to present the various portions thereof to the spray, and means controlled by said measuring means for determining the size of the outlet of the nozzle. 80
16. In a spraying machine, a spray nozzle, a rotatable rand crease guide for positioning the shoe with respect to the nozzle, and a work rest for engaging another portion of the shoe and mounted both slidably and rotatably so that various portions of the shoe may be presented to the spray from said nozzle. 90
17. In a spraying machine, a spray nozzle, a guide for the shoe to position the same properly with respect to the nozzle and constructed to shield portions of the shoe against the spray, and a work rest mounted for movement in a plurality of directions and along different paths so that various portions of the work may be presented to the nozzle. 100
18. In a spraying machine, a spray nozzle, means for measuring the work upon presentation of the same in proper position to receive spray from the nozzle and constructed and arranged to move with the work as the latter is turned to present the various portions thereof to the spray, and a member movable across the outlet of the nozzle and controlled by said measuring means for determining the size of the outlet of the nozzle. 105
19. In a spraying machine for shoes, a spray nozzle, a rotatable shield for limiting the application of spray to a shoe, and a work rest for engaging another portion of the shoe and mounted both slidably and rotatably so that all portions of the edge of the shoe may be presented to the spray from said nozzle. 110
20. In a spraying machine, a spray nozzle, a container for the spray material, means for forcing the spray material under pressure from the container and through the nozzle comprising a pipe for air under pressure, a valve in said pipe under the control 125
- 130

of the operator, and independent means for controlling at the nozzle the delivery of spray.

21. In a spraying machine, a spray nozzle, 5 a container for the spray material, means for forcing the spray material under pressure from the container and through the nozzle comprising a pipe for air under pressure, a valve in said pipe under the control 10 of the operator, and work-controlled means for controlling at the nozzle the delivery of spray.

22. In a spraying machine, a spray nozzle, a container for the spray material, means for 15 forcing the spray material under pressure from the container and through the nozzle comprising a pipe for air under pressure, a valve in said pipe under the control of the operator, and means for automatically controlling the delivery of spray from the 20 nozzle.

23. In a spraying machine, a spray nozzle, a reservoir for the spray material, a conduit for the spray material leading from the 25 reservoir to the nozzle, a passageway for air under pressure communicating with said reservoir and with the nozzle to force the spray material from the reservoir through the conduit and from the nozzle, and work 30 controlled means for determining the size of the outlet of said nozzle.

24. In a spraying machine, a spray nozzle, a reservoir for spray material, a conduit for spray material connecting the reservoir to 35 the nozzle, a passageway for air under pressure communicating with said reservoir and with said nozzle to force spray material through said conduit and from said nozzle, means under the control of the operator for 40 controlling the air passage, and automatic means for controlling the nozzle opening.

25. In a spraying machine, a spray nozzle, a reservoir for the spray material, a conduit for the spray material leading from the 45 reservoir to the nozzle, a passageway for air under pressure communicating with said reservoir and with the nozzle to force the spray material from the reservoir through the conduit and from the nozzle, work 50 controlled means for determining the size of the outlet of said nozzle, and means for actuation by the operator for controlling the supply of air to said nozzle.

26. In a spraying machine, a spray nozzle, 55 a reservoir for spray material, and a conduit connecting said reservoir with said nozzle and comprising a stationary and a movable portion so constructed and arranged as to be disconnectable without removal from the 60 machine, the construction and arrangement being such that air under pressure may be forced through the stationary portion of the conduit to remove the spray material therefrom.

65 27. In a spraying machine, a spray nozzle,

a reservoir for spray material, a conduit connecting said reservoir with said nozzle and comprising a stationary and a movable portion, a passageway for air under pressure, and means for moving the movable portion 70 of the conduit to connect the stationary portion of the conduit with the air passageway, the construction and arrangement being such that air under pressure may be forced through the stationary portion of the conduit to remove the spray material therefrom. 75

28. In a spraying machine, a spray nozzle, a reservoir for spray material, a conduit connecting said reservoir and said nozzle comprising a stationary part and a movable part, 80 a passageway for air under pressure surrounding said conduit, and a slide carrying said movable part and operable to disconnect the movable part from the stationary part of the conduit and to place said stationary part of the conduit in communication with the air passageway so that the spray material may be forced from said conduit.

29. In a spraying machine, a spray nozzle, a reservoir for spray material, a passageway 90 for air under pressure, a conduit connecting said reservoir and said nozzle comprising a stationary part and a movable part, and a slide for moving said movable part and operable to disconnect the movable part from 95 the stationary part of the conduit and to place said stationary part of the conduit in communication with the air passageway so that the spray material may be forced from said conduit.

30. In a spraying machine, a spray nozzle, a reservoir for the spray material, a conduit connecting the reservoir and the nozzle, a passageway for air under pressure communicating with said reservoir and said 100 nozzle to force spray material from said reservoir through the conduit and from the nozzle, said conduit comprising relatively stationary and movable portions, a slide for carrying said movable portion and operable 105 to disconnect said movable portion from the stationary portion and to place the stationary portion of the conduit in communication with the air passage, means for closing the air passage at the delivery end of the nozzle, 110 and means under the control of the operative for controlling the passage of air through said air passage and through the stationary 115 portion of the conduit to force the spray material therefrom and from the nozzle. 120

31. In a machine of the class described, a reservoir for liquid, a delivery device, a conduit connecting the reservoir and delivery device, a source of fluid pressure, and combined liquid-delivery and clearing connections included in the conduit between the reservoir and source and the delivery device. 125

In testimony whereof I have signed my name to this specification.

ALBERT E. JOHNSON,
